US00D960857S

(12) **United States Design Patent** (10) Patent No.: **US D960,857 S**
(45) Date of Patent: ** *Aug. 16, 2022

(54) **MOBILE PHONE**

(71) Applicant: **LG ELECTRONICS INC.**, Seoul (KR)

(72) Inventors: **Jiyoun Cha**, Seoul (KR); **Seongjae Lim**, Seoul (KR); **Seungbeom Park**, Seoul (KR); **Hyunggon Ryu**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **29/746,196**

(22) Filed: **Aug. 12, 2020**

(30) **Foreign Application Priority Data**

Feb. 13, 2020 (KR) 30-2020-0006517

(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the mobile phone that form no part of the claimed design.

1 Claim, 7 Drawing Sheets
